UNITED STATES PATENT OFFICE.

HERBERT L. ROBERTS, OF TORONTO, ONTARIO, CANADA, ASSIGNOR TO BUSINESS SYSTEMS, LIMITED, OF TORONTO, CANADA, A CORPORATION OF CANADA.

AUTOGRAPHIC REGISTER.

1,424,946.

Specification of Letters Patent. Patented Aug. 8, 1922.

Application filed July 27, 1918. Serial No. 247,039.

to all whom it may concern:

Be it known that I, HERBERT L. ROBERTS, a subject of the King of England, residing at Toronto, in the Province of Ontario, Dominion of Canada, have invented certain new and useful Improvements in Auto-graphic Registers, of which the following is a full and clear specification.

The present invention relates to improvements in autographic registers of the type in which a plurality of webs of paper containing printed forms, such as for sales slips, and longitudinally spaced pairs of registering perforations are periodically engaged by aligning pins to relatively register the superposed forms at the completion of each recording and feeding operation, so as to insure the detachment of slips of uniform length corresponding properly with the printed forms contained thereon.

In this class of machines it has heretofore been the usual practice to provide sheet registering or aligning devices in the form of pins which were designed to enter the register openings of the superposed webs and by their engagement with the walls of said openings, arrest the forward feed movement of all of the webs in properly aligned or registered position.

The main feature of the present invention comprises a novel registering or aligning mechanism for autographic registers. The improved machine is provided with suitable feeding mechanism for advancing the superposed webs of paper over a writing table from supply rolls supported beneath the writing table and feed arresting means controlled by automatically acting feeler and aligning fingers which operate upon the moving webs and move into the register openings of the webs for tripping the feeding mechanism and releasing its hold upon the webs to permit the webs to be drawn backwardly over the writing table until their backward movement is arrested by the engagement of the walls of the register openings with the feeler and aligning pins. This registering operation of the improved machine of the present invention differs from mechanisms heretofore employed in that the registry of the sheets is in a rearward direction, opposite to the feeding movement brought about by the release of the feed mechanism upon the webs. When the webs

are released from the feeding mechanism the rearward registry movement may be accomplished by the natural spring or set of the paper stock, or by any suitable mechanical means, but it is preferably effected by the employment of idler rolls, operating in a suitable slotted support in the machine frame, tending to draw back independently upon the superposed webs when the feeding mechanism releases them. These idler rolls may be actuated by gravity or by spring. In the case of gravity rolls, the rolls are mounted in properly inclined slots formed in their support.

The present invention also includes structural features of improvement in the paper roll supporting devices, the carbon roll support, the automatically controlled web feeding mechanism and the feeler mechanism which controls the feed and serves to register the perforated webs at the completion of each operation.

All these features will first be described with reference to the accompanying drawings and their novelty afterward pointed out more particularly in the annexed claims.

In said drawings,

Figure 1 is a plan view of an autographic register embodying the present invention;

Figure 2 is a side elevation of the same;

Figure 3 is an enlarged detail longitudinal sectional view showing one of the slotted supporting brackets for the gravity take up rolls;

Figure 4 is an enlarged vertical transverse sectional view, taken on the line 4-4 of Figure 2;

Figure 5 is a detail plan view of the carbon roll support, on a slightly larger scale;

Figure 6 is a detail transverse sectional view taken on line 6-6 of Figure 5;

Figure 7 is an enlarged detail end elevation of the machine;

Figures 8, 9, 10 and 11 are detail vertical longitudinal sectional views of the automatic feed and registering devices, said views being taken, respectively, upon the section lines 8-8, 9-9, 10-10 and 11-11 of Figure 7, in the directions of the indicating arrows.

The fundamental difference between the autographic register of the present invention and those that have heretofore been employed is the reversal of operation in the registering of the superposed perforated

webs or sheets of paper. In the present invention the aligning and feeler fingers are arranged to disconnect the web feed mechanism from the superposed webs to permit 5 a slight rearward motion of the webs over the writing table, the pins projecting through the openings in the webs arresting this rearward movement to place the superposed webs in proper registering relation. 10 This release of the feed in addition to the registering or aligning action of the feeler fingers is considered to be an important novel feature.

In the embodiment of the present invention, shown in the accompanying drawings, the machine is built up upon the usual side frames 1 and 2, connected by strengthening cross rods or tie bars, such as shown at 3 and by the operating parts hereinafter referred 15 to. 5 is a table frame pivotally mounted at its rear end upon a rod 6, mounted in the upper edges of side frames 1 and 2 and formed with downwardly presented side flanges 7 and 8 that snugly fit over the 20 upper edges of the side frames 1 and 2 when the table is in lowered operative position. The rear end of the table is cut away, as shown at 10, and mounted in this cutaway portion are downwardly presented bracket 25 flanges 14 and 15, formed with inclined slots 16, in which are freely mounted the journal ends of gravity idler rolls 20. These rolls 30 serve the double function of guiding the webs of paper from the supply rolls (presently referred to) to the writing table, and providing automatic means for moving the webs rearwardly over the table when the feed mechanism releases them for the purpose hereinafter explained. The number of 35 idler rolls 20 depends upon the number of webs that are to be handled in the machine. The accompanying drawings show four such rolls.

The previously printed and properly perforated webs or sheets are mounted in roll form as commonly practiced in this art. The rolls of prepared webs, preferably upon tubular spindles, such as is usually made of paper board, are mounted between bearing 45 cones arranged in pairs. Each pair of bearing cones comprises a stationary flanged head 25, mounted upon a rigid pin or lug, in one side frame and a movably mounted flanged head 26, mounted upon the inner 50 end of a sliding rotating pin 27, extending through bearing 28 in the opposite side frame and supporting an expansion spring 55 between the head 26 and the side frame for holding the head yieldingly in engagement with the tubular roll spindle. These 60 spring pressed rotating bearings for the rolls cause the rolls to be pressed against the stationary bearing heads with sufficient pressure to properly retard the feeding movement and since all of the rolls are pressed

toward the same side of the machine and are supported by the same form of devices it will be seen that the side edges of the superposed webs of paper will be properly aligned. This arrangement for supporting 70 the rolls affords convenient means for mounting and removing the rolls of paper and, if desired, proper handles (not shown) may be mounted upon the outer ends of the movable spindles 27 for actuating them. 75

Secured to the table side flange at the right are a pair of outwardly projecting bracket arms 35, 36, formed with vertical slots 37 adapted to receive the rod 40, which supports the roll of the required number of webs of carbon paper. These carbon webs are all wound upon the same rod, as is usual. This supporting rod 40 is formed with vertical slots 41 fitting over walls of the brackets 35, 36 to accurately position and support 80 the rod in the brackets. This rod 40 carries a disk or collar 45, which is adjustable longitudinally of the rod to engage and position carbon rolls of different lengths. This disk or collar 45 is formed with a peripheral 85 notch 46, in which engages a spring bail 50, having its opposite ends shaped into short crank arms 51, which engage openings 35^a, 36^a of the brackets. This spring bail 50 holds the disk or collar 45 in the desired 90 adjusted position upon the carbon roll supporting rod 40. 95

60 is a flanged cover plate pivotally mounted upon the rod 6 and formed with downwardly presented side flanges adapted 100 to fit over the side flange of table 5 at one side and the carbon roll supporting brackets 35, 36 at the opposite side. This cover plate forms a top housing for the carbon sheets and a marginal housing for the superposed 105 webs of paper, the plate being centrally cut out as shown at 61 to expose the central zones of the successive register blanks of the topmost web. This cover plate may carry suitable downwardly presented detents to 110 engage the carbon sheets to hold them against displacement in the operation of the register. Means may also be provided for locking the cover plate in closed position. These auxiliary devices are well known in 115 the art.

Mounted between the side frames at their forward or delivery ends is a suitable frame consisting of side plates 75 braced by the tie plates 76, 77, in which is mounted the 120 web feeding and aligning mechanisms which will now be described.

The upper feed roller 80 is journaled in the upright side members 75 just above the plane of the feed of the paper webs from the writing table. This upper roll 80 is formed with annular feed ribs or collars 81 a short distance from its ends, a central integral series of gear teeth 82, a similar series of gear teeth 83 at one end, and a combined 125 130

ratchet and driving gear 84 at its opposite ends. A crank handle 85 is secured to the projecting journal end of roll 80 at the left hand side of the machine, by which the feeding mechanism is manually operated.

5 A gravity stop dog or pawl 86 is pivoted at 87 to the frame piece 75 in position to constantly engage the combined ratchet and drive gear 84 to prevent backward rotation 10 of the same.

90 is the lower feed roller freely journaled in a pivoted carrying frame consisting of side plates 91, connected by tie rods 92, 93 which allow a slight relative yield between 15 the two side plates. The side plates are independently pivoted in the upright frame plates 75, 75 upon pivots 95. Tension springs 96 connect the tie rod 93 adjacent to frame plates 91 with a rock shaft 97 journaled in plates 75, to yieldingly hold the lower feed roller in peripheral engagement with the annular feed collars of the upper roll; the opposite ends of lower feed roller being acted upon independently to insure 25 accuracy in the feeding operation.

The rock shaft 97 has rigidly secured to it two bifurcated rock arms 98, the bifurcations of which straddle the tie rod 92 adjacent to plates 91 of the pivotally mounted 30 spring actuated frame of the lower feed roll. This rock shaft also has rigidly secured to it a rock arm 100, which projects upwardly and backwardly over the gear teeth 83 of the upper feed roll 80. To the free end of this 35 rock arm 100 is pivotally mounted at 101 a dog 102, engaged by a spring 103, carried by arm 100. This dog 102 is designed to move into engagement with the series of gear teeth 83 when released by the controlling 40 mechanism hereinafter described, for the purpose of positively rocking both side plates 91 of the frame carrying the lower feed roller to separate the feed rolls and release the webs therefrom.

45 105 is a horizontal plate formed with downwardly projecting end flanges 106, through which project the inner ends of pivot bolts 95. The flanged ends of the plate 105 are secured upon these pivot bolts 50 by suitable nuts. This plate 105 forms a short horizontal extension of the inclined writing table for accurately presenting the webs of paper to the feeding mechanism and the controlling and registering devices. 55 Plate 105 is formed with vertical slots 108 for the reception of the feeler and aligning fingers 110 which will now be described.

Journalized in the upright frame parts 75 above the feed rollers above described, is a 60 rock shaft 115, carrying loosely mounted rearwardly presented arms 116 and 117, upon which are loosely hung the feeler and aligning fingers 110. These fingers 110 reciprocate freely and vertically in suitable 65 guides 111, secured to the upright tie plate

76, and are adapted, when released, to press lightly upon the passing webs of paper and to enter the register openings in the webs, and project into the slots 108 of plate 105 as will hereinafter be explained.

70

The arm 116 is loosely mounted upon the shaft 115 by means of a set screw 116^a, engaging a flat or recess 115^b in shaft 115. A torsion spring 118 loosely surrounds the shaft 115, engaging at one end an overhanging finger 119, secured to plate 76, and at its opposite end the arm 116.

The arm 117 also has a limited "lost motion" connection with the shaft 115, by which it will be moved generally with the 30 shaft 115, but will also have a slight independent yielding movement with relation to the shaft. This back lash or lost motion can be provided for in any suitable manner, such as by the means above described 35 for mounting arm 116 upon the shaft 115. A torsion spring 121 surrounds the shaft 115, adjacent the arm 117, with one end attached to the bracket arm 122, secured to plate 76, and the other end attached to the 40 arm 117.

The purpose of this arrangement is to provide feeler fingers with a slight independent yielding motion in their action upon the passing perforated webs, so that 45 each finger can independently enter a perforation or series of partially registering perforations and can yield to any inequalities in the webs, without interfering with the operation of the other finger. This 100 independent spring action of the feeler registering finger is an important feature. The two feeler fingers co-operate in and permit the throw-out action only when both 50 fingers enter the register openings of the 105 webs.

129 is a rock arm secured to shaft 115, by which it is manually operated for raising and latching the feeler and aligning fingers 110 and associated devices.

110

The shaft 115 carries, centrally between its ends, a rigidly attached cam shaped collar 130, formed with a radial notch 131, in which engages a pawl or dog 132 pivoted at 133 in a bracket 134, secured to plate 115 76. A spring 135 connects the dog 132 with a bracket arm 136 projecting from plate 76.

140 is a vertically movable carrier plate 120 operating in suitable bracket arms 141—142 projecting from plate 76, the plate 140 being formed with an elongated slot 140^a, through which passes the shaft 115. Plate 140 is formed with a notch 140^b, in which 125 engages an eccentric pin 145, projecting laterally from the face of the cam shaped collar 130.

This carrier plate 140 has freely journaled upon it at 150 a segmental gear 155. A spring 156, connected at one end with the fixed bracket 141, above referred to, is at 130

tached at its opposite ends to an eccentric point 155^a of the segment gear 155. This spring 156 holds the carrier plate 140 horizontally elevated with the segment gear 155, 5 in its retracted out of mesh position. The oscillating gear segment 155 is presented alongside the dog 132, above referred to, said dog being provided with a pin 132^a which is presented in a segmental recess in 10 the adjacent face of the segment 155, so as to engage the shoulder or end wall of said recess when the gear segment is rotated to effect the disengagement of the dog 132 from the notched collar 130 to release the 15 feeler and aligning fingers above described. The rotation of gear segment 155 is effected by its intermeshing with the series of gear teeth 82, formed upon the upper feed roller 80, as above described. As will be herein- 20 after more fully described, in explaining the operation of the machine, it will be observed that when the shaft 115 is rocked for raising the feeler and aligning fingers, the notched collar 130 is thrown into engagement 25 with the dog 132 for holding the fingers elevated, the same action causing the carrier plate 140 to be moved downwardly for throwing the gear segment 155 into mesh with the series of gear teeth 82, 30 thereby setting the dog tripping device in readiness for automatic operation to release the feeler fingers when the succeeding operation takes place.

Adjustably mounted upon the shaft 115, 35 adjacent one end, is an adjustable cam 165, which operates in a yoke 170, which straddles and is supported by the cam 165 and is pivoted at its lower end 171 to the free end of the dog 102, above referred to. The 40 spring 103 acting through the dog 102 causes yoke 170 to closely follow the cam 165. The purpose of the cam 165 and yoke 170 is to raise or lower the dog 102 with reference to the ratchet wheel 83. When the 45 rock arm 129 rocks shaft 115 for raising feeler fingers 110 and latching them in elevated position, the cam 165 acting through yoke 170 raises dog 102 away from the ratchet teeth 83, thereby permitting the 50 springs of the lower feed roller to throw that roller into operative relation with the upper feed roll.

The operation of the improved register may be briefly explained as follows:

55 The several properly prepared webs are led from their supporting rolls over the guiding and take up rolls 20 to the writing table 5, over which the several webs of carbon paper are passed from the carbon 60 supporting roller, the carbon sheets being interposed between the record webs and secured against displacement in the manner well understood in this art.

The several superposed webs are threaded 65 between the upper and lower feed rolls and

adjusted into registered position with the aligning pins 110 passing through the registering openings of the several webs. In this adjustment at the start the feed rolls are spread apart by pressure on rock arm 100 so 70 that the webs may move freely in the machine and with relation to each other. With the webs properly positioned and the feed rolls thrown into action, the operator makes his record of a sale or other transaction of 75 which he desires a manifold record, and then, by rotating the crank 85 clockwise, feeds the several webs over the writing table and out of the delivery end of the machine. The feed is maintained until the aligning 80 and registering pins 110 drop into the perforations of the web, which action permits the spring actuated rock shaft 115 to move and lower the dog 102 into mesh with the rotating gear teeth 83, which draws rear- 85 wardly on the rock arm 100 for spreading apart the feed rolls and releasing the record webs from the grip of the feed mechanism. At the completion of this feed arresting operation, the dog 102 continues in engagement 90 with the gear teeth 83, thereby arresting the rotation of the feed rolls in a feeding direction and in co-operation with the dog 86 in its engagement with gear 84 locking the feed mechanism in the spread apart condition. 95

When the superposed webs are released from the feed rolls in the manner explained they are all pulled backwardly over the feed table by the idler take up rolls 20, moving by gravity in their inclined slots, each paper 100 web being independently pulled backwardly until it is arrested by the engagement of the walls of its registering perforations with the aligning pins. In this manner all of the webs are brought into accurate alignment 105 and registry, any slight inequality in the action upon one or more of the webs being completely corrected by the registering operation. In this way there is no danger whatever of accumulating error in registry 110 of the record webs.

Immediately following the registry of the webs, as explained, the operator depresses the rock arm 129, with the result that dog 102 is first raised out of engagement with 115 gear 83 to permit the lower feed roll to spring back into feeding relation with the upper roll to grip the webs between the rolls, and immediately following the grip of the webs by the feed rolls, the aligning and reg- 120 istering pins are withdrawn from the register openings and the rock shaft with its attached parts, above described, is latched in its retracted position. The projecting manifold records are then to be severed from the 125 webs by any suitable means. In the machine illustrated I have employed the tie plate 77 as a cutting bar up against which the projecting slips can be torn off. In this tearing off operation the webs are rigidly held 130

against movement by the grip of the feeding rolls.

When the succeeding record is made upon the superposed webs the operation is repeated, the initial movement of the upper feed roll causing the rotation of gear segment 155 against the action of spring 156 until its engagement with pin 132^a unlatches dog 132 from notched collar 130, with the result that the feeler fingers 110 are dropped upon the superposed webs just in rear of the register openings, which were employed for aligning the webs for the preceding record. The retarded release of the fingers 110 insures a sufficient movement of the webs to place the register openings out of range of the fingers. This release of the rock shaft 115 also partially lowers the dog 102, the adjustment of the controlling cam 165 being such that the dog will be held just out of engagement with the gear 83. The feeler fingers jointly sustaining the pressure of dog 102, spring 103 and yoke 170, and actuated independently by the controlling springs upon shaft 115, press lightly upon the superposed webs as they move forward from the writing table, under the action of the feed mechanism, until the fingers enter the next succeeding pair of register openings which causes a repetition of the operation above described in detail.

The flexibility of the pivoted frame for supporting the lower feed roller permits a limited relative movement between the opposite pivoted side plates 91. By this means the springs 96 are caused to act independently, to a limited extent, for maintaining effective feeding engagement of the opposite ends of roll 90 with the feed collars 81 of the upper roll. In the arrest of the feeding operation, both ends of roll 90 are positively moved away from upper roll by reason of rock arms 98 engaging rod 92 adjacent both side plates 91.

The feeler fingers are permitted to act independently within certain required limits, so that the danger of failure to properly align the superposed webs is reduced to a minimum. The construction is such that the feed is not released until both feeler fingers have passed through all of the perforations of the superposed webs.

The operation of the feeler fingers in disconnecting the mechanism for the paper is thought to be broadly novel. In addition to the release of the feed, the feeler fingers cooperate with the means for moving the webs rearwardly for registering the sheets in a manner which is exactly the reverse of the method heretofore employed. The construction is simple and the operation is more effective than those heretofore employed, since the errors of feed are corrected by pulling back the webs that have gone too far instead of depending upon uncertain mecha-

nism for feeding forward the webs which have not gone far enough. These means for registering webs in an autographic registering machine are considered to be broadly new, and I wish it to be understood that I do not intend to limit my claims to the specific forms of the feeding devices, the registering devices or the means for moving or shifting the webs in the registering operation.

The adjustable support for the roll of carbon webs is important, in that it permits the use of carbons of exactly the size required for the record slips that are being employed. The support can be adjusted to receive a wide roll of carbon sheets or a narrow roll, according to requirement. This affords a means for economizing in the use of the carbon sheets.

I claim:

1. In a machine of the character described, the combination of suitable web feeding means, and suitable registering means, with means actuated by the registering means for disengaging the feeding means from the web.

2. In a machine of the character described, the combination of suitable web feeding means, and suitable registering means, with means actuated by the registering means for disengaging the feeding means from the web, and web shifting means acting independently of the feeding means.

3. In a machine of the character described, the combination of means for feeding a web with a feeler device adapted to enter a perforation in the web and release the feed mechanism therefrom.

4. In a machine of the character described, the combination of means for feeding a web, with a feeler device adapted to enter a perforation in the web and means actuated by the movement of the feeler device for releasing the feeding means from the web.

5. In a machine of the character described, the combination of means for feeding a web, with a registering device adapted to enter a perforation in the web, means actuated by the movement of the registering device for releasing the feeding means from the web, and means independent of the feeding means for imparting a registering movement to the web.

6. In a machine of the character described, the combination of suitable feeding mechanism for advancing a web, a registering device therefor, means controlled by the registering device for automatically releasing the engagement of the feeding mechanism upon the web, and means for moving the released web in a direction reverse to the feeding movement until arrested by the registering device.

7. In a machine of the character described, the combination of suitable feeding mech-

anism for advancing a plurality of superposed webs, registering means for said webs, means controlled by the registering means for automatically releasing the engagement 5 of the feeding mechanism upon the webs and means acting independently upon the several webs for moving the released webs until arrested by the registering means.

8. In a machine of the character described, 10 the combination of suitable feeding mechanism for advancing a plurality of superposed webs, registering means for said webs, means controlled by the registering means for automatically releasing the engagement 15 of the feeding mechanism upon the webs and means acting independently upon the several webs for moving the released webs in a direction reverse to the feeding movement until arrested by the registering means. 20

20. 9. In a machine of the character described, the combination of suitable feeding means, and suitable registering means, with means actuated by the registering means for arresting the operation of the feeding means, 25 and means actuated by the feeding means for initiating the operation of the registering means.

10. In a machine of the character described, the combination of suitable feeding 30 means, and suitable registering means, with means actuated by the registering means for arresting the operation of the feeding means, restraining means holding the registering means out of action, and means actuated by 35 the feeding means for disengaging said restraining means to permit the registering means to move into action.

11. In a machine of the character described, the combination of suitable feeding 40 means, and suitable registering means, with means actuated by the registering means for arresting the operation of the feeding means, restraining means for holding the registering means out of action, and timed retarding 45 means actuated by the feeding means for disengaging said restraining means to permit the registering means to move into action after the start of the feeding movement.

50. 12. In a machine of the character described, the combination with suitable feed mechanism for advancing a plurality of superposed webs, automatic means for shifting the webs rearwardly, suitable registering 55 fingers arranged to enter registering perforations in the several webs to arrest and register the rearward movement of the webs, and automatic means actuated by said fingers for disengaging the feeding mechanism 60 from the webs.

13. In a machine of the character described, the combination of suitable feed mechanism, suitable registering fingers adapted to enter registering perforations in 65 a web, means actuated by the movement of

the registering fingers for disengaging the feed mechanism from the web, and means for moving the web rearwardly and registering it upon said fingers when the feed mechanism is released. 70

14. In a machine of the character described, the combination of a writing table, a take up roll movably mounted adjacent to said table, a web passing over said take up roll to said table, suitable feed mechanism 75 for moving the web over said table, suitable sheet registering pins, and means actuated by the movement of the registering pins for disengaging the feed mechanism from the web. 80

15. In a machine of the character described, the combination of a writing table, a plurality of take up rolls movably mounted adjacent to said table, and adapted to individually engage webs superposed upon 85 said table, suitable feed mechanism for moving the webs over said table, suitable sheet registering pins adapted to enter registering perforations in the superposed webs and means actuated by the registering pins for 90 disengaging the feed mechanism from the webs to allow the take up rolls to move the webs rearwardly and register them upon said pins. 90

16. In a machine of the character described, the combination of a writing table, roller supporting guideways mounted adjacent to said table at an angle to the plane of the table, a plurality of gravity take up rolls 100 movably mounted in said guideways, adapted to individually engage webs superposed upon said table, suitable feed mechanism for moving said webs over said table, suitable registering devices and means for automatically disengaging the feed mechanism from 105 said webs to permit the take up rolls to shift the webs rearwardly until arrested by the registering devices. 105

17. In a machine of the character described, the combination of a writing table, 110 roller supporting guideways mounted adjacent to said table at an angle to the plane of the table, a plurality of gravity take up rolls movably mounted in said guideways, and individually engaging webs superposed 115 upon said table, suitable feed mechanism for moving said webs over said table, suitable registering devices and means controlled by said registering devices for automatically disengaging the feed mechanism from said 120 webs to permit the take up rolls to shift the webs rearwardly until arrested by the registering devices. 120

18. In a machine of the character described, the combination of a feed roll 125 mounted in fixed bearings, a spring pressed frame pivotally mounted adjacent to said fixed feed roll, a second feed roll journaled in said frame, a rock shaft carrying rock arms engaging the said spring pressed 130

- frame, a rock arm projecting from said rock shaft, means arranged between said fixed roll and said rock arm for operating said frame, and suitable registering means controlling the connection between said roll and said rock arm.
19. In a machine of the character described, the combination of a feed roll mounted in fixed bearings, a spring pressed frame pivotally mounted adjacent to said fixed feed roll, a second feed roll journaled in said frame, a rock shaft carrying rock arms engaging the said spring pressed frame, a rock arm projecting from said rock shaft, a gear upon said fixed roll, a dog carried by said rock arm adapted to engage said gear for operating said frame, and suitable registering means controlling the action of said dog.
20. In a machine of the character described, the combination of a pair of feed rolls, means for moving one of said rolls relatively to the other, suitable feeler registering fingers supported above the path of a web, a spring actuated rock shaft supporting said fingers, a latch arranged to hold said shaft against movement with said fingers elevated, means actuated by said shaft for operating said roll moving means and means actuated by one of said rolls for tripping said latch.
21. In a machine of the character described, the combination of a pair of feed rolls, means for moving one of said rolls relatively to the other, suitable feeler registering fingers supported above the path of a web, a spring actuated rock shaft supporting said fingers, a latch arranged to hold said shaft against movement with said fingers elevated, a segment gear having lost motion connection with said latch, and automatic means for operably connecting said segment gear with one of said feed rolls.
22. In a machine of the character described, the combination of a pair of feed rolls, means for moving one of said rolls relatively to the other, suitable feeler registering fingers supported above the path of a web, a spring actuated rock shaft supporting said fingers, a latch arranged to hold said shaft against movement with said fingers elevated, a vertical movable support actuated by said rock shaft, a segment gear journaled upon said support, a spring device normally holding said segment gear in retracted position, a gear upon one of said feed rolls with which said segment gear is adapted to mesh and a lost motion connection between said segment gear and said latch.
23. In a machine of the character described, the combination of a table, means for feeding a web over said table, a rock shaft, suitable registering fingers carried by and having lost motion connection with said rock shaft, independent springs acting upon said fingers and means controlled by said rock shaft for releasing the feeding means.
24. In a machine of the character described, the combination of a table, means for feeding a web over said table, a sheet registering device including a spring actuated rock shaft, a latching device for holding said rock shaft in its inactive position, means controlled by said rock shaft for disengaging the feed mechanism, and means actuated by the feed mechanism for tripping said latch.
25. In a machine of the character described, the combination of a table, a pair of feed rolls for feeding a web over said table, a registering device including a spring actuated rock shaft, means controlled by said rock shaft for separating said feed rolls to arrest their feeding operation, a dog adapted to latch said rock shaft in its inactive position, and a toothed member thrown into engagement with one of said feed rolls by the inactive movement of said rock shaft and having suitable connection with said dog for tripping it when the feed rolls are operated.
26. In a machine of the character described, the combination of a table, a pair of feed rolls for feeding a web over said table, one of said rolls being journaled in a pivotally mounted spring actuated frame, means for moving said roll supporting frame, including a rock shaft suitably connected with the frame and having a rock arm projecting therefrom, a dog mounted upon said rock arm, a gear upon one of said feed rolls with which said dog is adapted to engage and suitable registering means having controlling connection with said dog.
27. In a friction-roll manifolder employing perforated form strips, a drive roll and a cooperative pressure roll for feeding said strips, means for relaxing the pressure between the rolls after feeding said strips a predetermined distance, form registering means for engaging form perforations at the time of said pressure relaxation, and form adjusting means adapted to act upon the forms.

HERBERT L. ROBERTS.
